VARIABLE CONDENSER

Original Filed April 17, 1922

UNITED STATES PATENT OFFICE

CARL A. HELLMANN, OF WASHINGTON, DISTRICT OF COLUMBIA

VARIABLE CAPACITOR

Original application filed April 17, 1922, Serial No. 553,754. Divided and this application filed October 25, 1924. Serial No. 745,769.

My invention relates to condensers.

The object of the present invention is to provide an improved variable condenser, adapted for general use in the electrical arts and particularly adapted for use in connection with high frequency electrical work, such as the radio art or carrier wave wire signaling.

More specifically, an object of the invention is to provide a condenser having several distinct ranges of capacity, any one of which may be readily selected for service by suitable means.

Other objects and advantages of the invention will appear from the present specification and the accompanying drawings, wherein all the figures are purely diagrammatic. In said drawings:

Fig. 1 illustrates mechanical means for varying the range of a condenser by shifting its rotary member axially, thereby putting more or less plates in position to become active;

Fig. 2 illustrates the same device as Fig. 1, the rotary member being shown in a different position; and

Fig. 3 illustrates a detail of Fig. 1.

This case is a division of application Serial No. 553,754, filed April 17, 1922, and which has matured into Patent Number 1,525,778 dated February 10, 1925.

As shown in Figs. 1, 2 and 3, the movable element 1 of the condenser comprises a plurality of sectors 2, which may be of any of the shapes or materials disclosed in the parent case, mounted on a shaft 3, supported rotatably and slidably by a bearing 4 near one end and supported by the panel 5 near its other end. The shaft 3 has a longitudinal slot or key-way 6 therein and also has a series of annular grooves 7 in the portion adjacent the bearing 4. A screw 18 has an end 8 projecting into the key-way 6, or one of the grooves 7, both being of proper width to receive it.

The bearing 4 is supported by the back 9, which serves in the usual manner to support the stationary plates or sectors 10 of the condenser, by means of the usual posts 11 only one of which is shown, which, if the plates 2 be of dielectric material, will be pref-

erably made as shown in Fig. 12 of the parent case, but if all the plates be metallic, will be made in the ordinary manner. As illustrated, the front of the condenser is the panel 5 itself, though obviously in a portable condenser unit, front and back would be alike in general. A sleeve 12 carrying the dial 13 is keyed slidably as at 19 on the shaft 3, and is mounted to rotate in the panel 5. A spring washer 14 held by a nut 15, serves to retain the dial 13 in proper position against panel 5. The movable sectors 2 are keyed to the shaft 3 by means of the same key-way 6, and may be adjusted into the correct position and then secured to the shaft in any known way. The shaft terminates in a knob 16 and has a series of graduations 17 adjacent said knob.

In operation, the condenser will be manipulated just as is any other rotary condenser, except that if plates of the type disclosed in the parent case be used, its effective angle is between 180° and 360° instead of being limited to 180° or less as in previously known types. When the dial is at its zero position, that is, when the movable sector plates are entirely clear of the fixed plates, namely in the position shown in Fig. 2, the slot 6 is in register with the lug 8 and in this position it is possible to adjust the shaft 3 longitudinally to bring any one of the grooves 7 in alignment with the lug 8. These grooves are spaced the same distance apart as the sectors, so that whenever a groove is in alignment with the lug 8, the sectors are automatically aligned with the spaces between the fixed plates, and may then be rotated by knob 16 to vary the capacity in the usual way. In this manner, the range of capacity may be varied, and as many sectors as desired may be put in service; the said number being indicated by the scale 17 and the forward edge of sleeve 12 cooperating therewith. The dial 13 will always indicate the angular position of the movable sector, in the usual manner.

It is observed that while I have described a condenser having several unique features, it is not necessary that all said features be present, and my invention is not to be limited except as specified in the following claims.

1. A rotary variable condenser comprising fixed and movable plates, and means for varying the number of plates in active service, comprising a shaft carrying the movable plates, which is movable longitudinally, and is graduated to indicate automatically the number of plates in such active service. 5
2. A rotary variable condenser comprising a shaft carrying a movable series of plates, and a cooperating set of fixed plates, said shaft being movable longitudinally in steps which are equal to the spacing of the plates to vary the number of plates in service. 10
3. A rotary variable condenser comprising a shaft carrying a movable series of plates, a cooperating set of fixed plates, said shaft being movable longitudinally to vary the number of plates in service and means for preventing such longitudinal movement when the plates are interleaved. 15
4. A rotary variable condenser having a plurality of stationary plates and a plurality of rotary plates cooperating therewith to provide a continuous variation of capacity, means for varying the number of electrically-adjacent plates, comprising a shaft carrying the rotary plates, and having a series of circumferential grooves, and a longitudinal groove therein, and a stationary member co-operating with said grooves to restrain the movement of said shaft. 25
5. A rotary variable condenser having a plurality of stationary plates and a plurality of movable plates and means for varying the number of stationary plates electrically-cooperating with the movable plates, whereby different ranges of capacity variation are provided, said means comprising a shaft carrying the movable plates and movable longitudinally a distance materially greater than the spacing of the plates. 35
6. A rotary variable condenser having movable plates and stationary plates, relative rotation of said plates serving to vary the capacity continuously in the usual manner and additional means independent of the rotation of the plates for varying the capacity range, said means comprising structure for selectively varying the total number of movable plates mechanically adjacent to stationary plates. 45
7. A rotary variable condenser having movable plates and stationary plates, relative rotation of said plates serving to vary the capacity continuously in the usual manner and additional means independent of the rotation of the plates for varying the ranges of capacity produced solely by the movable plates with respect to the stationary plates in successive steps. 55
8. A rotary variable condenser having rotary plates and stationary plates whereby a continuous variation of capacity may be obtained and independent means for varying the number of plates in service, including a shaft carrying the rotary plates and having circumferential grooves thereon spaced apart distances corresponding to the spacing of the plates. 60
9. A rotary variable condenser having a stationary member and a rotary member co-operating therewith, said rotary member being mounted on a shaft, said shaft being mounted for independent axial and rotary movements, and means preventing one only of these types of movement at certain positions of the shaft. 70
10. A rotary variable condenser having a stationary member and a rotary member co-operating therewith, said rotary member being mounted on a shaft, said shaft being mounted for independent axial and rotary movements, and means preventing one only of these types of movement at certain positions of the shaft and the other type only in certain other positions of said shaft. 75
11. In a condenser, a set of stationary plates, a shaft, means to operate the same, and a set of plates mounted on the shaft and adapted to lie parallel to the stationary plates and be moved into and out of position with respect to the same to provide an initial adjustment of the capacity, said shaft being movable bodily to alter the location of the movable set of plates with relation to the stationary set, in steps equal to the spacing of the plates. 80
12. In a condenser, a plurality of stationary plates, a plurality of movable plates, and means to rotate said movable plates in unison, certain of said movable plates being so arranged that the rotation thereof will alter the capacity of the condenser and certain of said movable plates being so arranged that the rotation thereof will not affect the capacity of the condenser. 90
13. A device of the character described, including a plurality of stationary plates, a plurality of rotary plates, said rotary plates constituting a unit and being adjustable longitudinally with respect to said stationary plates, to an extent sufficient to vary the number of rotary plates adjacent the stationary plates. 100
14. A condenser of the character described having a plurality of capacity ranges, comprising a plurality of cooperating capacity producing elements, and means for producing stepwise relative motion of said cooperating elements to select a desired capacity range, said elements being further movable relatively to one another to provide a variation of capacity within the selected range. 110
15. A condenser provided with substantially parallel, spaced elements which are relatively rotatable to provide a capacity variation and are further adjustable longitudinally relatively to one another in steps substantially equal to the spacing of the elements to an extent sufficient to provide dis- 120
16. A condenser having a plurality of capacity ranges, comprising a plurality of cooperating capacity producing elements, and means for producing stepwise relative motion of said cooperating elements to select a desired capacity range, said elements being further movable relatively to one another to provide a variation of capacity within the selected range. 130

tinct ranges of capacity variation upon said relative rotation.

16. A condenser provided with a stationary element and a rotary element, said rotary element being adjustable longitudinally in distinct steps to provide a number of maximum capacities, said rotary element being also adjustable from a substantially zero capacity to said different maximum capacities.

10 17. The process of varying the capacity of a condenser having relatively movable parts at least one of which comprises a plurality of spaced, substantially parallel, capacity producing elements, which comprises first relatively moving said parts in one sense to vary the number of said elements which will be put in service, and thus selecting a desired capacity range, and thereafter relatively moving said parts in another sense to produce a final adjustment of capacity within the selected range.

18. The process of varying the capacity of a condenser which includes two relatively movable capacity producing elements, at least one of which comprises a plurality of substantially parallel spaced members, said process consisting in first relatively moving the elements substantially transversely to the general direction of the parallel members, to an extent sufficient to change the number of such members which will become interleaved during the second step of the process, which step consists in relatively moving the elements in the planes of their members to vary the amount of interleaving of said members.

19. The process of varying the capacity of a condenser which has two relatively movable capacity producing elements at least one of which comprises a plurality of spaced members, which consists in first relatively moving the two elements in one sense to select the spaced members which are to contribute to the capacity and then relatively moving the elements in another sense to vary the amount of interleaving of the two elements to thus vary the capacity produced.

20. A rotary variable condenser comprising a rotor and rotor shaft and a stator, a relatively large panel and means for mounting said rotor and stator directly upon said panel, comprising a support secured at one end directly to the panel and rigidly supporting the stator, and means rotatably supported directly by the panel and forming a support for the rotor shaft, the panel itself serving as the sole front supporting and spacing means for the said rotor and stator, thus dispensing with the usual front end plate heretofore used for such purpose.

21. A rotary variable condenser comprising a rotor and rotor shaft and a stator, a relatively large panel and means for mounting said rotor and stator directly upon said panel, comprising a support secured at one end directly to the panel and rigidly sup-

porting the stator, a bearing rotatably supported directly by the panel and forming a support for the rotor shaft, the panel itself serving as the sole front supporting and spacing means for the said rotor and stator, thus dispensing with the usual front end plate heretofore used for such purpose, and resilient means arranged between, and cooperating with, said bearing and panel to take up any play.

In testimony whereof I affix my signature.
CARL A. HELLMANN.
